FEED IDLER CORNER

Gerald L. Kitson, 9709 Belding Road,
Rockford, Mich. 49341

Filed July 6, 1971, Ser. No. 160,262

Term of patent 14 years

Int. Cl. D15—99

U.S. Cl. D55—1 C

FIG. 1

FIG. 2

FIG. 3

FIG. 4

FIG. 5

FIG. 7

FIG. 6

FIG. 1 is a top plan view of the feed idler corner embodying my new design, the broken line outline illustrating the top wall thereof in a rotated position.

FIG. 2 is an elevation of the feed idler corner shown in FIG. 1.

FIG. 3 is an elevation of the feed idler corner rotated 90° to that of FIG. 2.

FIG. 4 is a face view of the feed idler corner of FIG. 1 rotated 45° to that of FIG. 2 and FIG. 3.

FIG. 5 is an elevation opposite to the face view shown in FIG. 4.

FIG. 6 and FIG. 7 are opposing perspective views corresponding, respectively, to FIG. 4 and FIG. 5. (not shown) corresponds to the plan view shown in FIG. 1.

I claim:

The ornamental design for a feed idler corner, as shown and described.

A bottom plan view of the poultry feeder corner (not
